US00D667786S

(12) **United States Design Patent**
Ueda et al.

(10) **Patent No.:** **US D667,786 S**
(45) **Date of Patent:** **** Sep. 25, 2012**

(54) **CHARGER FOR A RECHARGEABLE BATTERY**

(75) Inventors: **Arinobu Ueda**, Tokyo (JP); **Ryo Okura**, Tokyo (JP)

(73) Assignee: **Sony Corporation**, Tokyo (JP)

(**) Term: **14 Years**

(21) Appl. No.: **29/371,727**

(22) Filed: **Aug. 1, 2011**

Related U.S. Application Data

(63) Continuation of application No. 29/347,299, filed on Nov. 25, 2009, now Pat. No. Des. 642,516.

(57) **CLAIM**

The ornamental design for a charger for a rechargeable battery, as shown and described.

DESCRIPTION

FIG. 1 is a top, right, front perspective view of a charger for a rechargeable battery showing our new design;

FIG. 2 is a bottom left, front perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a bottom plan view thereof.

Portions in broken lines are for illustrative purpose only and form no part of the claimed design. The dot-dash broken lines define but are not included in, the boundaries of the claimed design.

1 Claim, 6 Drawing Sheets
